SCRUBBING MACHINE

Keith N. Krier, Neil F. Brown, and Steven J. A. Waldhauser, Minneapolis, and John N. Polivka, Hopkins, Minn., assignors to Tennant Company, Minneapolis, Minn.

Filed Apr. 18, 1972, Ser. No. 245,293

Term of patent 14 years

Int. Cl. D15—05

U.S. Cl. D49—9.1

Fig. 2

FIG. 1 is a side elevational view of a scrubbing machine, as viewed from the right side thereof, embodying our new design;

FIG. 2 is a left side elevational view thereof;
 FIG. 3 is a front view thereof;
 FIG. 4 is a rear view thereof;
 FIG. 5 is a top view thereof; and
 FIG. 6 is a bottom view thereof.

We claim:

The ornamental design for a scrubbing machine, substantially as shown.
